UNITED STATES PATENT OFFICE.

FREDERICK C. LINDSEY, OF MILWAUKEE, WISCONSIN.

HEAVY-OIL VAPORIZER.

Application filed April 25, 1923. Serial No. 634,629.

This invention relates to charge forming devices, and more specifically, to an improved heavy oil vaporizer which involves the principles and general construction of that which is shown in my two co-pending applications, Serial Numbers 412,885 and 534,800, being substantially a division of the former application, but embodying improvements shown in the later application.

10 The main object of this invention is to provide a highly efficient and thoroughly practical device for vaporizing the heavier liquid fuels such as kerosene, distillate, and the like, in connection with means to convey or conduct the resultant gas to a heater or heat retainer which keeps it in the gaseous state while being conveyed to a carbureter or other device for completing its preparation for combustion.

15 A further object is to provide a device of this character that includes a passage for the products of combustion of the gas it produces, so that these heated products of combustion are utilized for heating the oil to 20 the point of vaporization and then keeping it vaporized while passing through the heater to the carbureter.

25 A further object is to provide a device of this character that is very compact, durable, 30 of comparatively simple and inexpensive construction, and very conveniently opened or disassembled for removing incrustations or other detrimental accumulations which might result from the use of oils containing 35 foreign substances.

However, a further object of this invention is to provide for so thoroughly vaporizing the oil, that there will be left no residue of oil in the vaporizer.

40 Other objects and advantages will be pointed out or implied in the following details of description, in connection with the accompanying drawings in which:—

45 Fig. 1 is a vertical, central sectional view. Fig. 2 is a horizontal sectional view along the line 2—2 of Fig. 1. Fig. 3 is a horizontal sectional view along the line 3—3 of Fig. 1. Fig. 4 is a detail sectional view along the line 4—4 of Fig. 1.

50 Referring to these drawings, in detail, in which similar reference characters refer to similar parts throughout the several views, the body of the vaporizer includes six primarily separate sections (according to the present embodiment, though not of necessity), viz, sections 5, 6, 7, 8, 9, and 10.

However, the sections 5 and 6 are preferably made integral or united by brazing or electric welding at the plane directly above the line 3—3. In like manner, the sections 7 and 8 are preferably brazed or electrically welded to one another at the top of the section 7, the latter being preferably a hollow cylinder, while the members 6 and 8 are perforated or apertured disks or plates of sheet metal provided with annular shoulders 6^a and 8^a about which snugly fit the lower ends of the sections 7 and 9 respectively. The sections 5 and 9 are provided with apertured ears 11 through which extend screws or bolts 12. In view of the foregoing, the device's main body may be considered as constituting three separable sections held together by the screws 12, the section 10 in this connection being a removable part of the upper 55 section 9—10, while the middle section 7—8 may also include heating tubes 13 which are preferably rigidly united with the disk 8 by any appropriate means, it being shown that these tubes extend through and are fitted 60 in apertures indicated at 14 of the disks 8 and 6. However, these tubes are removable from the apertures at 14 of the latter or lower disk; so that when the bolts 12 are removed, the upper section 9—10 can first be 65 removed from the middle section, and then if necessary or desirable, the middle section 70 can be removed from the lower section 5—6 by withdrawing the tubes 13 from the lower apertures at 14, thereby gaining access to 75 the gas-generating chamber which surrounds 80 the main portions of the tubes 13.

For feeding oil into the gas-generating chamber, I provide an oil-introducing nozzle 15 for each one of the tubes 13, of which 85 there are seven in the present instance, and these nozzles are preferably connected with a single source of oil supply, as shown in my applications (referred to above). For 90 this purpose I provide supply conduits 16 which preferably include L's, unions 17, and flexible pipes 18, only one of the latter being visible in Fig. 1, some of them being 95 hidden, and others being omitted. The nozzles 15 extend through the wall of the cylinder 100 7 and into relatively wide peripheral grooves 19 where they deliver the oil to be vaporized. The nozzles are preferably slotted or 105 grooved across their ends, as shown at 15^a, so as to feed oil even if the ends of the 110 nozzles abut against the tubes 13, although it is intended that there be a slight space

between the nozzles and tubes. Below the grooves 19, the heating tubes are each provided with a series of peripheral capillary or narrow and narrowly spaced grooves 20, 5 or a single helical groove in the form of a screw-thread, the purpose of which is to retard the flow of oil down the tubes from the nozzles and to spread the oil around the tubes so as to utilize every part of the heating surfaces of these tubes. By this means, 10 the oil becomes thoroughly vaporized before it reaches the lower ends of the tubes, so there is no residual oil in the bottom of the vaporizing chamber. It is to be understood that the oil is drawn into the vaporizing 15 chamber in consequence of a partial vacuum being created therein by the suction of the engine to which this device is attached or attachable, the intake manifold of the engine being connected to a conduit which 20 includes an L or tubular oil vapor outlet 21 which extends through the apertured plate or partition 8 and has its outlet end extending into the exhaust gas outlet 22 of the 25 section 9. The latter outlet forms part of a heating conduit or heat-retainer, so that the heat of the exhaust gas is retained for keeping it from condensing while being conveyed to the carburetor.

30 The oil vaporizing tubes 13 are heated by the heating fluid or exhaust gases or products of combustion which enter through an inlet or conduit 23 which may be either a 35 part of or united with an internal combustion engine's exhaust manifold. This inlet is part of the section 6, and the latter is formed with spreaders or angular ribs 24 and 25 each having its apex alined with the centre of the inlet, so that as the exhaust 40 gases enter, they are spread laterally in opposite directions for distributing them equally among the heating tubes, while also deflecting the hot exhaust gases upwardly towards and into the tubes. If these spreaders or distributors were absent, there would 45 be a tendency for the hot gas to pass by the tubes near the inlet, and "piling up" or accumulating pressure at the farthest tubes, would impart more heat to these tubes than 50 to the nearer ones, while also sending a relatively small amount of the hot exhaust gases through the tubes which are laterally disposed relative to the centre of the inlet 23.

55 The section or plug 10 is merely a closure for an access opening through which a brush

or other article can be inserted for cleaning the interior of the tubes 13 through which the hot products of combustion pass from the lower section to the upper section of the vaporizer.

60 It is not intended to limit this invention to the exact construction and arrangement here shown and described, but changes may be made within the scope of the inventive idea as implied and claimed.

65 What I claim as my invention is:

1. In an oil vaporizer, the combination of a hollow body comprising an upper compartment, a lower compartment, and an intermediate compartment, the latter having 70 an oil inlet and an oil vaporizer outlet, the latter provided with an oil vapor conducting tube, this intermediate compartment having a tubular oil vaporizing member extending therethrough into open communication with the said upper compartment and lower compartment and into proximity to said oil inlet for receiving oil on its outer surface from said oil inlet; said lower compartment having an inlet for receiving a heating fluid which passes through said vaporizing member into said upper compartment; said upper compartment having a heating outlet 75 which forms part of a heat-retaining passage and surrounds and encloses a part of 80 said gas-conducting tube for the purpose specified.

2. In an oil vaporizer, the combination of an oil vaporizing chamber, a plurality of upright heating tubes extending through the 90 interior of said chamber, a compartment under said chamber and having a closed bottom under said heating tubes while its upper end is in open communication with said tubes, said compartment having an inlet for 95 a heating fluid, this inlet being substantially horizontal, spreaders extending up from said closed bottom and extending angularly thereacross and being spaced from said heating tubes so that a part of the heating fluid 100 can pass thereover to the farthest tube while another part of the heating fluid is deflected laterally and upward to the nearer heating tubes, means to convey oil onto said heating tubes, and means to convey the generated 105 vapor from the vaporizing chamber.

In testimony whereof I affix my signature.

FREDERICK C. LINDSEY.
